UNITED STATES PATENT OFFICE

MATTHEW S. QUINLIVEN, OF LOS ANGELES, CALIFORNIA

FIREPLACE AIR HEATER

Application filed January 9, 1930. Serial No. 419,617.

The invention relates to improvements in fireplace air heaters and it aims to provide a new and improved construction, in which effective provision is made for the heating and circulation of air, so that the heater not only radiates heat from the fire and the hot metal, but produces added efficiency by means of circulated hot air currents.

With the foregoing in view, the invention resides in the novel subject matter hereinafter described and claimed, description being accomplished by reference to the accompanying drawings.

Fig. 1 is a front elevation partly in vertical section.

Figs. 2 and 3 are vertical sectional views on lines 2—2 and 3—3 respectively of Fig. 1.

Figs. 4 and 5 are horizontal sectional views substantially on lines 4—4 and 5—5 respectively of Fig. 1.

Fig. 6 is a fragmentary front elevation partly in section, showing a modification.

The form of construction illustrated in Figs. 1 to 5 will first be described, and it may be explained that while in both forms of construction shown, I have illustrated most parts as if cast in a single body, it is to be understood that the structure may be formed from separate sections bolted or otherwise secured together, and that some of said sections may be of heavy material such as cast iron or steel, while others may be of lighter constructions, formed either totally or partially from comparatively thin sheet metal. Such variations are merely mechanical and are not therefore illustrated.

The numerals 8 denote two hollow vertical front posts each having a horizontal partition 9 near its lower end, cool air inlets 10 and a cool air outlet 11 below said partition, and a hot air inlet 12 and hot air outlets 13 above said partition, the outlets 13 being above the inlet 12. The inlets 10 and outlets 13 are preferably disguised by appropriate gratings or the like which may be effectively "worked in" with the designs of the posts.

Extending between and secured to the lower portions of the posts 8, is a horizontal cool air-receiving flue 14 having forwardly turned ends 15 communicating with the cool

air outlets 11 of said posts. Behind this flue 14, is a hollow back wall 16 whose upper portion may be turned forwardly as at 17, if desired. Two vertical end walls 18 are secured at their rear portions to the rear wall 16, said end walls being hollow and in communication with said rear wall 16, including its portion 17. The upper front portions of the walls 18 are preferably reduced in height as indicated at 19, are secured to the posts 8 and communicate with the hot air inlets 12 of said posts. The lower portions of these walls 18, at the front ends of the latter, are suitably secured to the flue 14 at the junctures of the main portion of this flue with its forwardly turned ends 15.

A front-to-rear flue 20 extends from the lower central portion of the front flue 14 to the lower central portion of the rear wall 16 and communicates with said flue 14 and wall 16. Also extending between the flue 14 and wall 16, is a grate 21 of any desired construction, said flue and wall being provided with appropriate ledges 22 upon which the grate rests. By preference, this grate is positioned above the flue 20.

Either a solid fuel fire may be built upon the grate 21, or a liquid or gaseous fuel burner may be placed upon said grate with appropriate heat-conducting material extending from the burner to the grate portions 14, 16 and 18. Consequently, these parts become highly heated to effect heating and circulation of air. Cool air from the room enters through the inlets 10, passes through the cool air outlets 11 into the front flue 14, is heated within the latter, then passes rearwardly through the flue 20 and is further heated in the latter. The warm air from flue 20 is received in the back wall 16 and from this wall travels into the end walls 18, being thus heated to high temperature. The hot air enters the upper portions of the posts 8 through the hot air inlets 12, and discharges through the outlets 13 into the room. By taking the relatively cool air into the lower portion of the structure and discharging the hot air from its upper portion, a continual and desirable circulation of air is effected in the room. Moreover, heating is attained by

this hot air circulation, as well as by direct radiation.

Any desired front guard 23 may be used with the structure above described, being secured either to the end walls 18, to the front flue 14, or possibly to both.

Fig. 6 illustrates a modification of construction. In this view the front flue 14^a does not communicate with the interior of the posts 8^a and the latter are provided with no cool air inlets. Instead, the front or any desired portion of the flue 14^a, is provided with appropriate inlets 10^a for the cool air. Otherwise, the construction may be considered the same as that above described.

It will be seen from the foregoing that novel provision has been made for carrying out the objects of the invention. The various details disclosed may be followed if desired, but within the scope of the invention as claimed, variations may be made.

I claim:

1. A fireplace air heater comprising two hollow vertical front posts each having a relatively low hot air inlet and a comparatively high hot air outlet, a front horizontal cool air receiving flue extending from one of said posts to the other, a hollow rear wall behind said front flue, a front-to-rear flue extending between and communicating with said front flue and said rear wall, two hollow end walls secured to and communicating with said rear wall, the front portions of said end walls being secured to said posts and communicating with said hot air inlets thereof, and a grate extending between the lower portions of said back wall and said front flue.

2. A fireplace air heater comprising two hollow vertical front posts, each of said posts having a horizontal partition near its lower end, a cool air inlet and a cool air outlet below said partition, a hot air inlet above the partition and a hot air outlet above said hot air inlet; a front cool air receiving flue extending horizontally between said posts and communicating with the cool air outlets thereof, a hollow rear wall behind said front flue, a front-to-rear flue extending between and communicating with said front flue and said rear wall, two hollow end walls secured to and communicating with said rear wall, the front portions of said end walls being secured to said posts and communicating with said hot air inlets thereof, and a grate extending between the lower portions of said back wall and said front flue.

3. A fireplace air heater comprising two hollow vertical front posts, each of said posts having a horizontal partition near its lower end, a cool air inlet and a cool air outlet below said partition, a hot air inlet above the partition and a hot air outlet above said hot air inlet, a front horizontal cool air flue having forwardly turned ends secured to said

posts and communicating with said cool air outlets thereof, a hollow back wall behind said front flue, a front-to-rear flue extending from said front flue to said rear wall and communicating with both thereof, hollow end walls whose rear portions communicate with said rear wall, the front ends of said end walls being reduced in width and communicating at their upper corner portions with said hot air inlets of said posts, the lower front portions of said end walls being secured to said front horizontal flue at the junctures of its body and end portions, and a grate extending between said front flue and the lower portion of said rear wall.

In testimony whereof I have hereunto affixed my signature.

MATTHEW S. QUINLIVEN.
